METHOD OF FREQUENCY OR PHASE MODULATION

David G. C. Luck, Woodbury, N. J., assignor to
Radio Corporation of America, a corporation
of Delaware

Application August 22, 1935, Serial No. 37,270

20 Claims.

(Cl. 250—6)

My invention relates to the transmission and reception of energy at radio frequency. In particular, my invention relates to a method of frequency or phase modulating a transmitted wave, and 5 means for receiving and demodulating the wave.

One of the objects of my invention is to phase or frequency modulate radio frequency energy.

Another object is to phase modulate a radio wave a larger number of degrees than is at present obtainable by conventional transmission apparatus.

Another object is to convert a phase modulated wave into a series of modulated impulses.

A further object of my invention lies in the 15 means for receiving and demodulating a phase or frequency modulated wave.

Other objects will appear from the accompanying drawings, specification, and claims.

In the accompanying drawings,

20 Figure I represents in schematic outline form one embodiment of my invention applied to a transmission system.

Figure II illustrates in outline form the nature of a receiving system employing one form 25 of my invention.

Figure III is a graph illustrating a saw-tooth wave without modulation.

Figure IV is a graph illustrating a saw-tooth wave with modulation,

30 Figure V is a graph illustrating a series of impulses derived from a saw-tooth wave,

Figure VI is a characteristic curve of a current limiter which may be used in the derivation of impulses from a saw-tooth wave,

35 Figure VII is a diagram of a constant frequency oscillator,

Figure VIII is a circuit diagram of a current limiter,

40 Figure VIII(a) represents the characteristic curve of the current limiter shown in Figure VIII.

Figure IX represents the combination of a current limiter and a saw tooth generator,

Figure X is a diagram of a modulator circuit,

45 Figure XI is a diagram of an impulse operated electron relay,

Figure XII illustrates a wave shaping circuit,

Figure XIII is a diagram of a circuit for wave shaping and carrier suppression, and

50 Figure XIV represents a modification of my invention.

If the amplitude of an oscillatory current is varied in accordance with a desired signal, the oscillation is said to be amplitude modulated. Likewise, if the frequency of an oscillatory current is varied in accordance with the signal to be

transmitted, the oscillation is said to be frequency modulated. The rate of change of the phase of an oscillatory current is termed the frequency of that current. Therefore, it may be seen that a frequency modulated current may be 5 termed a phase modulated current. The difference between the two depends upon the particular relation between the variations of the original signal and the variation of phase or frequency produced by it. The system I am about to describe may be adapted to either phase or frequency modulation.

With the existing systems it has been difficult to obtain phase modulation exceeding thirty degrees without serious distortion, if the mean frequency of the transmission is to remain stable. It is difficult to apply phase modulation to a crystal controlled oscillator system. In the application of my invention I can obtain phase modulations of the order of one hundred and eighty 20 degrees and employ a constant source for the mean frequency of transmission. The explanation of the operation of my system may best be understood by referring to Figure I.

Any constant frequency source of radio energy 25 supplies the radio frequency oscillations 3. These oscillations are impressed on a duplex saw-tooth generator 5 which converts the wave form to the sawtooth wave represented by the graphs 7 and 9 by a process of limitation, differentiation, 30 rectification, and integration. Each of these wave forms corresponds with the frequency of the oscillatory source 1 but the phase of one of the sawtooth oscillations 9 is one half period behind that of the other sawtooth oscillation 7. 35 The sawtooth oscillations 7 and 9 are impressed respectively on the modulators 11 and 13. Although I have described the oscillations as saw tooth in wave form, any triangular wave form may be employed.

40 The modulators 11 and 13 convert the wave form by limitation, differentiation, and rectification to a series of equally spaced positive impulses of equal amplitude and in opposing phase relationship. These impulses are indicated by the graphs 15 and 17. The impulses 15 and 17 act on the impulse operated electron relay 19 which controls a local source of energy. The lower impulses 17 start the currents in the electron relay 19 and the upper impulses 15 stop the currents 50 in the relay 19. The currents from the output circuit of the relay 19 may be represented as a square flat top wave 21. The currents represented by the square wave form 21 may now be shaped by appropriate filter circuits 23, whose 55

resultant output is represented by the graph 25. These currents are then impressed on the transmitting antenna 27. It should be understood that amplifiers or frequency multipliers may be interposed between the wave shaping circuit 23 and the antenna. The frequency multipliers increase the frequency modulation, as well as the carrier frequency. Independent control of the final carrier frequency may be effected by any of the known methods which permit the addition or subtraction of other frequencies.

Thus far my description has been limited to the transmission of radio frequency currents without impressing on these currents the modulation of the desired signal representing currents. If a source of signal representing energy is impressed on the microphone 28 or the like, and passed through an amplifier 31, modulating currents are generated as represented by the curve 33. These modulating currents may be linked to the modulators 11 and 13. The modulators 11 and 13 have the effect of varying the relative timing of the two series of positive impulses 15 and 17 which may then be represented as variably spaced impulses 35 and 37. If these impulses 35 and 37 are impressed on the electron relay 19 the resultant output will be a square wave 39 which is accurately phase modulated in accordance with the modulation current 33.

After the square wave 39 is applied to the wave shaping circuit 23, the resulting wave is a phase modulated sinusoidal wave 41. An inspection of this wave form 41 shows that its phase varies and its amplitude is constant; in other words, it is phase modulated.

Before describing the details of the circuits employed for transmitting and receiving phase or frequency modulations in accordance with my invention, I shall briefly set forth the theory underlying my invention. If a saw tooth wave is generated by suitable means, the wave form may be illustrated by Figure III. The frequency of the saw tooth wave should be high compared with the frequency of the desired modulating signals. If a modulating signal of lower amplitude than that of the saw tooth is added to the saw tooth wave, the result may be illustrated by Figure IV. If the saw tooth wave shown in Figure III is applied to a current limiting circuit having the limiting characteristic shown in Figure VI, the result will be in effect the switching on of current by the passage of the signal upwards through a particular value (zero for example), and the switching off of current by the downward passage of the signal through the same voltage. This effect may be further described as a set of dots of current separated by spaces when no current flows. The rate of repetition of the dot-space cycle being constant, while the relation of dot length to space length is varied in accordance with the modulating signal. These dots may be converted, by differentiation with respect to time, into a set of short pulses, marking the starting and stopping of each dot, as shown in Figure V.

The value of the dot signal of amplitude a , at any time t , during the n th dot, the original dot repetition period being T , is

$$A_d = -2a\left(\frac{t}{T} - n\right) \quad (1)$$

The value of the modulating signal of amplitude b (b is less than a) is

$$A_m = b \cdot f(t) \quad (2)$$

where the function $f(t)$ describes the time varia-

tion of the modulating signal. The condition for a dot to end, such that the total signal of Figure IV is zero, is

$$\frac{t}{T} - \frac{b}{2a} \cdot f(t) = n \quad (3) \quad 5$$

A phase modulated wave, of unmodulated frequency

$$\frac{1}{T} \quad 10$$

may be defined as

$$A = A_0 \sin \left[\frac{2\pi t}{T} - \frac{2\pi B}{360} f(t) \right] = A_0 \sin \varphi \quad (4)$$

where B is the maximum phase shift in degrees produced by the modulating signal, which varies with time in accordance with the function $f(t)$. The phase modulated wave passes through the zero value in one particular direction whenever the angle φ (which is the phase of the wave) has a value of any integral multiple of 2π radians. Therefore the times when the phase modulated wave is zero are given by

$$\frac{t}{T} - \frac{B}{360} f(t) = n \quad (5) \quad 25$$

where n is any integer.

Comparison of equations (3) and (5) shows clearly that the instants at which a set of modulated dots stop are the same as those at which the phase modulated sine wave passes through zero. A phase modulated wave, corresponding to a set of dots of repetition period T (or frequency N) and amplitude a , modulated by a signal of amplitude b , has an unmodulated period $\tau = T$ (frequency N), and is modulated

$$B = \frac{b}{a} \times 180$$

degrees. The passages of this dot-frequency wave through zero in the other direction are at the instants of stopping of dots formed by modulating with the same signal a second saw tooth wave identical with the first but being displaced in time by a half period.

The foregoing theory, taken in conjunction with the explanation of Figure I, makes it clear how the respective impulses of a pair of modulated dot trains with a half dot period relative time displacement can be used to switch on and off a current which produces a series of square top waves which will be accurately phase modulated in accordance with the original modulating signal. The negative voltage impulses, indicated dotted in Figure V, having no useful effect, have been removed by rectifying means. The resulting square wave may be accurately phase modulated by any amount less than 180 degrees by the modulating signal. The square wave may be sent through a wave shaping filter to give an approximate sine wave, which as has already been described, will be phase modulated up to almost 180 degrees.

I shall now describe the detailed circuits represented in block forms 1, 5, 11, 13, 19, and 23 of Figure I.

The constant frequency oscillator 1 of Figure I may be any of the well known oscillators. One such oscillator is the piezo-electric control shown in Figure VII. The piezo-electric crystal 151 is connected to the grid and cathode of thermionic tube 153. In the anode circuit of the tube 153 is connected resonant circuit 155 and a suitable anode current source 157. The output terminals of the oscillator are represented as 159-161. 75

In this, and the following schematic diagrams, the filament heating battery or power source is omitted. It should be understood that any suitable power sources for filaments, bias, or anodes 5 may be used.

The duplex saw-tooth generator 5 of Figure I may be described as two units; one, a current limiter illustrated in Figure VIII; the other, a saw tooth generator proper represented as Figure IX. 10 The current limiter, Figure VIII, is composed of two thermionic tubes 171 and 173. The input to the limiter is represented as a pair of terminals 175-177 and its output as two terminals 179-181. The two tubes 171 and 173 are resistance coupled. The input bias voltage of the first tube 171 is adjusted to normally prevent anode current from flowing in the anode circuit of the first tube 171. The second tube 173 is adjusted to permit full anode current to flow. 15 As the input voltage across the input terminals 175-177 is increased a potential will be reached at which anode current will flow in the first tube 171. The current in the anode resistance of the first tube 171 places a negative bias on the second tube 173 which tends to block currents in the anode circuit of this tube 173. The limiting action may be illustrated by the curve of Figure VIII(a).

The effect of the current limiter is illustrated by its reshaping of the wave form of the constant frequency oscillation 183 of Figure IX, and may be shown as a flat top wave form 185 after passing through the current limiter 187. The circuit and apparatus represented by the block form 187 corresponds with the current limiter just described in connection with Figure VIII. The limiter may also amplify. The voltages represented by the flat top wave form 185 are applied to the differentiator circuit 189-191 which comprises a capacity 189 having a large reactance and a resistance 191 of relatively small value. The impulses produced by this differentiator are impressed on the input of a thermionic tube 193. The output circuit of this tube 193 includes an integrator circuit composed of a resistance 195 of large value and a capacity 197 of relatively small reactance. The output terminals of this part of the circuit are represented as 199-201. The impulses are reversed in phase by the phase reversing tube 203 whose output circuit is connected to the input of a thermionic tube 205. The tubes 193 and 205, which include the integrator circuits, are similar with respect to their functions and output circuits. Both tubes have input biases which are normally adjusted to cut-off. The bias makes these tubes 193 and 205 rectify—or respond to only positive impulses. The output terminals of the second integrator and rectifying tube 205 are shown as 207-209. It should be understood that these tubes 193 and 205 may be triodes, tetrodes or any suitable thermionic tubes.

The modulators 11 and 13 of Figure I are represented diagrammatically as Figure X. The one of the duplex saw tooth oscillations is impressed on the input terminals of the modulator 211-213. These terminals connected to the input circuit of a thermionic tube 215. The signal representing voltages, which may be amplified, are impressed on the input terminals 217-219 of a second tube. The input of this tube 221 is connected to the input terminals 217 and 219 through a potentiometer 223 which permits adjustments of the degree of modulation produced. Since the anode circuits of the first two tubes of

the modulator 215-221 are made common, the signal and saw tooth currents are added in the common anode resistor 222. The voltage across the common resistor is impressed on the input terminals of the current limiter 225. The current limiter, represented as 225, may be of the type previously described in connection with Figure VIII.

The output of the current limiter is connected to a differentiator circuit composed of a low 10 value of resistance 227 and a capacity 229 of relatively high reactance. The potentials across 227 are impressed on the input terminals of a rectifier 231. This rectifier is biased to cut-off so that it is only responsive to positive impulses. 15 The output terminals of the rectifier are represented as 233-235. A similar modulator circuit to the one just described is employed to modulate the other saw tooth oscillation. That is, a pair of 20 circuits similar to Figure X are employed to perform the functions of modulating represented by 11 and 13 of Figure I.

The impulse operated electron relay illustrated by block 19 is shown in schematic form in Figure XI. The impulse relay employs a pair of thermionic tubes 237 and 239 which are connected as a multi-vibrator. The multi-vibrator has a free frequency of the order of the desired carrier frequency. The "on impulses" are impressed on the input 245-247 of one of the pair of tubes and the "off impulses" are impressed on the input circuit 241-243 of the other tube 239 of the pair. The output circuit of the pair of tubes 237 and 239 is represented by terminals 249-251.

The final step in the transmission system is the wave shaping. The complicated sideband pattern of the phase modulated rectangular wave 39 is such that, if the carrier frequency is of the order of twelve times higher than the highest frequency present in the modulation, (or the ratio 40 may be somewhat lower than twelve times if the higher modulation frequencies are of relatively low amplitude), a band pass filter circuit may be used. A single section band pass filter circuit is shown in Figure XII. The input circuit of the 45 filter is composed of a resonant circuit 253. The output circuit is composed of a second resonant circuit 255. The two resonant circuits are coupled by any suitable type of mutual coupling, such as M. The degree of coupling is one of the 50 factors which determines the relative width of the frequency band which the filter will pass. The effect of the filter is to re-shape a square wave form 39 of Figure I to a sinusoidal wave 41 of the same figure. The output of the wave shaping 55 circuit, which may comprise several such filter sections, may be amplified and is coupled to a work circuit which may be a transmission line, antenna or the like.

The same circuits may be used to frequency 60 modulate by the simple expedient of connecting an integrator circuit, comprising a large resistance and a capacity of relatively low reactance, between the microphone 29 and the amplifier 31. The integrator circuit is similar to 65 Figure XIII with the carrier frequency trap circuit omitted.

Frequency and phase modulated signals cannot be demodulated, without deleterious distortion, by impressing the transmitted wave on one or 70 more tuned circuits resonant to the mean transmitted wave frequency and detecting by any of the conventional detector circuits. This conclusion follows from the fact that conventional detectors are operated by amplitude variations 75

of the signal representing voltages, rather than variations in the frequency of the received currents. A frequency modulated wave may be translated by employing a series of tuned circuits adjusted so that oscillatory currents of the mean frequency of the transmitted wave drive the circuits at a frequency other than their resonant period. The circuits themselves will then translate the frequency modulated wave into an amplitude modulated wave which may be detected by any of the well known detecting circuits. Such a method is relatively inefficient. The phase modulated wave may be received by supplying a local carrier and conventional detector, but this method produces bad distortion for phase modulation exceeding twenty or thirty degrees. This is a well known method, but I prefer the arrangement of Figure II for the reception and translation of a phase modulated wave transmitted by means of the arrangement of Figure I.

In Figure II a source of phase modulated energy is connected to the input terminals of a radio amplifier 101. The amplifier may consist of the conventional thermionic tubes and tunable circuits responsive to a band of frequencies centered on the mean transmission frequency. A local oscillator 103 is synchronized by any of the known means, with the oscillator 1 of the transmitter shown in Figure I. The currents 105 and 107, representing the received wave and the local oscillations, are fed into impulse generators 109 and 111. The impulse generators by limitation, differentiation and rectification, produce a series of sharply defined positive impulses represented by the graphs 113 and 115. The positive impulses 113 act as the "off impulses" and correspond to the impulses 15 generated by the modulator 11 at the transmitter Figure I, if the wave is unmodulated, and to the modulated impulses 35 if the transmitter is modulated. The "on impulses" are uniformly spaced as represented by the positive impulses of the graph 115 and correspond to the impulses 17, or to the negative impulses 45 of the transmitted wave when the wave is unmodulated. The positive impulses 113 and 115 are applied to the impulse operated electron relay 117 which corresponds to the relay 19 at the transmitter. The output of the electron relay 50 117 will be a unidirectional pulsating current of square wave form, such as 119, and comprised of a series of dot impulses of a constant rate of repetition but having a ratio of time on to time off which varies in accordance with the modulation of the received signal. These impulses are capable of operating a loud speaker directly but, as a large percentage of radio frequency energy is present, I prefer to reshape the modulated dot frequency wave 119. The square wave may be 55 shaped by a filter 121 which corresponds broadly to the wave shaping circuit 23 of the transmitter. I also integrate, and reject the carrier wave frequency. The output from the filter 121 will be a wave corresponding to the original of the signal frequency modulating wave 33 impressed on the transmitter of Figure I.

The circuits represented by the block diagrams 109, 111, 117 and 121 will now be described in detail by schematic circuit diagrams.

70 Radio amplifiers, 101 of Figure II, are so well known to those skilled in the art that a detailed showing is unnecessary. The amplifier, per se, is not part of my invention. The same is true of the local oscillator 103 which may be of any 75 conventional type. The oscillator may be locked

in step with the carrier frequency by coupling between the radio amplifier and the oscillator. In any event the local oscillator should have a constant frequency output and remain in step with the carrier, as is necessary for any phase modulation translating system.

The impulse generators 101 and 111 may be a pair of circuits similar in arrangement to Figure X with the tubes preceding the current limiter and their circuits omitted. One of the pair of impulse generators has its input terminals, which correspond to those of the previously described current limiter 225, coupled to the radio amplifier 101 of Figure II, and the other input terminals are connected to local oscillator 103 of the same figure. The outputs of this pair of circuits are connected to the impulse relay corresponding to 117 of Figure II. The detailed schematic diagram of the impulse relay circuits is shown in Figure XI.

The output of the impulse operated relay is connected to the input of the wave shaping circuit. The essentials of this circuit, represented as 121 of Figure II, will be found in Figure XIII. The input terminals 251, 259 of the wave shaping circuit are connected to integrator elements. These elements include a resistance 261 which is of large value, and a capacity 263 whose reactance is relatively small. It is desirable to remove the carrier frequency. This may be done by shunting a series resonant circuit, comprising inductance 265 and capacity 267, across the output of the wave shaping circuit. The series circuit is resonant to the carrier frequency and preferably of relatively low resistance at resonance. The output of the wave shaping circuit is represented as a pair of terminals 269—271. A loudspeaker or other signal responsive device is connected to the output of the wave shaping circuit.

In connection with Figure I, I have described how a constant frequency oscillation may be converted into two series of positive impulses, how these impulses may be phase or frequency modulated and impressed on an impulse controlled relay. The modulated currents of square wave 45 form set up by the relay are shaped and become phase or frequency modulated sinusoidal oscillations. These oscillations may be transmitted and demodulated in accordance with the system described in connection with Figure II. My conception of this system is broader than the exact process as illustrated. It is by no means essential that the method of employing my invention follow the exact sequences or all of the steps I have described. For example, in certain cases the wave 50 shaping may be omitted in transmission or reception.

As an example of another modification within the scope of my invention, the receiving system of Figure II may be used, with slight modifications, as a transmitter of modulated impulses, or dot transmission. For simplicity and brevity I have illustrated these modifications in the block diagram of Figure XIV. A detailed description is hardly necessary. The dotted lines, through the impulse relay block, indicate direct impulse keying of the transmitter. The only new element is the phase modulator which may be any of the phase modulating devices well known to those skilled in the art. The remaining functions may be performed by the several circuits already shown and described in connection with the foregoing description and figures.

These modifications are merely suggested by way of example. Other obvious modifications 75

within the scope of my invention will occur to those skilled in the art. I do not limit my invention to the foregoing description, but desire that only such limitations shall be placed thereon as are necessitated by the prior art and set forth in the appended claims.

I claim:

1. The method of communication which comprises generating two saw tooth oscillations substantially in synchronism and in opposing phase, converting said saw tooth oscillations into a series of positive impulses, applying said impulses to start and stop a flow of local energy, transmitting waves generated by said local energy, converting said transmitted waves into a series of positive impulses, generating a second series of positive impulses, alternately applying the impulses of both mentioned series to start and stop the flow of current in a local source thereby generating currents, and impressing the last mentioned currents on a signal translating device.

2. The method of communication which comprises generating two oscillatory currents of saw tooth wave form substantially in synchronism and opposing phase relation, converting said oscillatory currents into two series of positive impulses, applying a modulating signal-representing current to said series of impulses, applying the modulated series of impulses to start and stop currents from a local source of energy, transmitting modulated waves generated by said local energy, converting said transmitted modulated waves into a series of positive impulses, generating a second series of positive impulses, alternately applying the impulses of both mentioned series to start and stop the flow of current in a local source thereby generating modulated currents in accordance with the transmitted modulations, and impressing the last mentioned modulated currents on a signal translating device.

3. The method of communication which comprises generating a substantially constant frequency oscillatory current, converting said current into two currents substantially in contraphasal relation and of saw tooth wave form, converting said saw tooth wave form currents into two series of positive impulses, applying a modulating signal current to said series of impulses, alternately applying said modulated positive impulses to generate and stop the generation of currents, transmitting said generated currents, converting said transmitted generated currents into a series of positive impulses, initiating a local oscillation in synchronism with the first mentioned oscillatory current, converting said local oscillation into a series of positive impulses, alternately impressing positive impulses from the two series of impulses to start and stop the flow of current in a local source, and impressing the last mentioned current on a translating device.

4. The method of communication described by claim 3 and characterized by the further step of wave shaping the currents generated from said local source.

5. The method of communication described by claim 3 and characterized by the further steps of wave shaping before transmitting and wave shaping before impressing the currents on a translating device.

6. The method of transmitting an oscillatory current which comprises generating a saw tooth oscillation, generating a second saw tooth oscillation synchronous and in substantially contraphasal relation with the first saw tooth oscillation, converting said saw tooth oscillations into

a series of positive impulses, applying said impulses to start and stop a flow of a local source of energy, and transmitting waves generated by said local energy.

7. The method of transmitting an oscillatory current which comprises generating a saw tooth oscillation, generating a second saw tooth oscillation synchronous and in substantially opposing phase relation with said first saw tooth oscillation, converting said saw tooth oscillations into a series of positive impulses, applying said impulses to start and stop a local source of energy, reshaping the wave representing said local energy and transmitting waves of said reshaped energy.

8. The method of transmitting a modulated oscillatory current which comprises generating an oscillation of saw tooth wave form, generating a second oscillation of saw tooth wave form synchronous and substantially in contraphasal relation with the first mentioned saw tooth oscillation, converting said saw tooth oscillations into a series of positive impulses, applying modulating signal representing currents to said series of impulses to vary their relative timing, applying the modulated positive impulses to start and stop a wave whose energy is derived from a local source, and transmitting waves of said modulated wave energy.

9. The method of transmitting an oscillatory current which comprises generating an oscillatory current of substantially constant frequency, converting said current into two currents of saw tooth wave form, retarding one of said currents to an opposing phase relation with respect to the other current, converting said two currents into a series of positive impulses, applying said currents to effect the operation of a relay controlling a local source, whereby a series of square topped waves are transmitted from said local source.

10. The method of transmitting an oscillatory current which comprises generating an oscillatory current of substantially constant frequency, converting said current into two currents of saw tooth wave form, adjusting the timing of one of said currents to the other so that a substantially contraphasal relation exists, converting said two currents into a series of positive impulses, applying modulating signal currents to said series of impulses to vary their relative timing, applying the modulated impulses to start and stop a wave whose energy is derived from a local source, and transmitting waves created from said local source.

11. The method of transmitting an oscillatory current which comprises generating a substantially constant frequency oscillatory current, converting said current into two currents of saw tooth wave form bearing an opposing phase relationship, converting said two currents into two series of positive impulses, applying the positive impulses to start and stop a wave whose energy is derived from a local source, reshaping the wave from said local source, and transmitting the reshaped wave.

12. The method of transmitting an oscillatory current which comprises generating a substantially constant frequency oscillatory current, converting said current into two currents bearing a substantially opposing phase relation and having a saw tooth wave form, converting said two currents into a series of positive impulses, applying modulating signal currents to said series of impulses to vary their relative timing, applying the modulated impulses to start and stop a wave whose energy is derived from a local source, re- 75

shaping the modulated wave from said local source, and transmitting said reshaped modulated wave.

13. The method of transmitting phase modulated radio frequency energy which comprises generating a substantially constant radio frequency current, converting said current into a pair of oscillations having an opposing phase relation and a saw tooth wave form, converting said pair of oscillations of saw tooth wave form into two series of positive impulses, modulating said series of positive impulses with a desired signal current whereby the relative timing of the impulses is accurately varied in accordance with the modulating signal, alternately impressing the positive impulses to start and stop the flow of current in a local source whereby oscillatory currents of square wave form are generated, reshaping said square wave form, and radiating the reshaped phase modulated oscillatory currents.

14. The method of translating phase modulated oscillatory currents which comprises converting said currents into a series of positive impulses, generating a series of positive impulses in substantially opposing phase relation and in synchronism with the positive impulses of unmodulated received oscillatory currents, applying both series of said positive impulses to start and stop the flow of current in a local source thereby generating currents of a square wave form, and impressing the last mentioned currents on a signal translating device.

15. The method of translating phase modulated oscillatory currents which comprises converting said currents into a series of positive impulses, generating a series of positive impulses in substantial contraphase relation and synchronism with positive impulses of unmodulated received oscillatory currents, applying both series of said positive impulses to start and stop the flow of current in a local source thereby generating currents of a square wave form, reshaping the currents of said square wave form in accordance with the original signal modulations, and translating said currents into indications corresponding to the original signal energy.

16. The method of receiving and translating phase modulated oscillatory currents which comprises selectively amplifying said currents, generating a local oscillation substantially in synchronism with the mean frequency of said phase modulated currents, converting said received currents and said local oscillations into two series of positive impulses, alternately impressing each of said positive impulses to start and stop the flow of a local current thereby generating a pulsating current having a square top wave form, and translating said pulsating current into signal indications.

17. In a system of the character described, a constant frequency oscillation generator, an impulse generator for converting said constant frequency oscillations into two series of positive impulses, an electron relay, a source of energy in the output circuit of said relay, means for impressing the positive impulses on said relay whereby the output circuit is alternately energized and deenergized, means for altering the wave form of the output currents of said electron relay and means for transmitting said altered output currents.

18. In a system of the character described in claim 17, means for modulating said positive impulses.

19. In a system of the character described, means responsive to phase modulated currents, a local oscillator of constant frequency, means for converting said phase modulated currents and said local oscillations into two series of positive impulses, an electron relay, a source of energy in the output circuit of said relay, means for impressing said series of positive impulses on said relay whereby its output circuit is energized and deenergized by said local source of energy, and means for translating currents in the output circuit of said relay into intelligible signals corresponding to said phase modulation.

20. In a system of the character described by claim 19, a rejector circuit connected to the output of said electron relay to eliminate radio frequency oscillations contained in the output currents of said relay.
